UNITED STATES PATENT OFFICE.

WILLIAM S. ELDER, OF PHILADELPHIA, PENNSYLVANIA, ASSIGNOR TO JULIUS HIRSH, OF PHILADELPHIA, PENNSYLVANIA.

UNDERGARMENT.

Application filed May 27, 1920. Serial No. 384,566.

To all whom it may concern:

Be it known that I, WILLIAM S. ELDER, a citizen of the United States, residing in Philadelphia, Pennsylvania, have invented 5 certain Improvements in Undergarments, of which the following is a specification.

My invention relates to improvements in undergarments, and relates more particularly to the formation of the shoulder loops 10 of the garment, the object of the invention being to provide a certain novel and improved method of forming the said shoulder loops and of finishing or trimming the upper portion of the garment, which results in 15 a considerable saving of material and in a greatly improved article.

In the attached drawings:

Figure 1, illustrates an undergarment made in accordance with my invention;

20 Fig. 2, is a view of a portion of a garment illustrating a modified form of my invention;

Fig. 3, is a view of a portion of a garment illustrating a further modification of 25 my invention, Fig. 4, is a fragmentary section on the line 4—4, Fig. 1.

In the accompanying drawings, 1 indicates the upper portion of the body of an undergarment, formed in the present instance 30 from a tubular blank of knitted material by cutting away portions at the top to form the neck opening 2 and the arm openings 3, 3, these neck and arm openings being such that their lower edges, as clearly illustrated, 35 are in approximate alignment. Extending around the edges of the arm openings 3, I have shown, in the present instance, strips of tubing 4, 4 sewed to the body, while similarly secured to the body at the edges of 40 the neck opening 2 is a continuous strip of tubing 5, the free portions of which extending between the front and back of the said body form the shoulder loops 6 of the garment.

45 In making this garment, I prefer first to attach the strips 4 to the edges of the arm openings 3, 3, after which the strip 5 may be attached to the edges of the neck opening and to the free ends of the strips 4. A 50 draw-string 10 passed through the strip of tubing 5 and extending through an opening at the front of the garment completes this portion.

The usual method of forming the shoulder 55 loops of garments of this type has been to

extend the strips of tubing 4, which are attached to the edges of the arm openings so as to form loops similar to the loops 6, extending between the front and back of the garment, the loops 4^a thus formed lying side by side with the said shoulder loops 6, as shown in broken lines in Fig. 1, and being suitably attached thereto along the adjacent edges. In the compound shoulder loop thus formed, it has been customary to have the 60 ends of the arm strips meet at the lowest point of the arm openings, the seam thus formed being objectionable, while the said compound shoulder loops are unnecessarily wide and give the garment an unattractive 65 appearance.

With my improved shoulder loop formation, I not only obtain a more attractive looking garment and eliminate the objectionable seam under the arm pit, but I also 70 accomplish a substantial saving in materials, this saving besides involving the amounts of tubing and sewing thread employed, also appearing in the actual amount of knitted fabric required to form the body of the 75 garment.

The saving in the tubing and in the sewing thread will be apparent, since the amount of tubing saved in each garment is equal to a single strip twice the length of 80 the shoulder loop itself, while the sewing thread saved is that which would be employed in sewing the loops of the compound straps together.

The saving in the material of the garment itself will be best understood by reference to Figure 1 of the drawings. In Figure 1, the outer strip of a compound shoulder loop is illustrated in broken lines, and it will be noticed that with this formation, the V-shaped point 7^a of the body 1, which lies between the two strips of tubing below their point of juncture at the front of the garment, extends to a point considerably higher than the corresponding portion 7 in the new garment the angle between the strips being acute in the old type garment whereas in the present instance the arm strips 4 join the neck strip approximately at 90 right angles. This is necessary if it is desired to provide an attractive and well-made garment, since if in the old type the arm tubing were carried in to meet the neck tubing at a lower point, an abrupt bend would 95 result in the said arm tubing which would 100 105 110

be both unsightly and poor practice. The tubular blank from which the body is formed must be long enough to cover the entire length of the garment from the bottom to the topmost point, and it will thus be seen that in a garment of the new type of any specified length, the blank required will not have to be so long as in a garment of the same length of the old style. A still further saving in the material of the body can be realized by extending the length of the shoulder loops, this, in the present garment, being possible without spoiling the appearance of the garment, as would be the case were the old form of shoulder loop equally lengthened.

In Figure 2, I have shown a modified form in which instead of the tubing 4 extending around the edges of the arm openings of the garment, I show the edges trimmed with a shell stitch 4^b.

It will be clear that many forms of trimming other than tubing may be employed with no departure from the invention, although tubing is preferred as lending itself exceptionally well to the use of the draw-string at the neck. Thus, for example, as shown in Fig. 3, I may use instead of the tubing 6, an open lace-work trimming 11 through which may be passed a ribbon 12 to be used as a draw-string if desired. It is further brought out that as regards the edges of the arm openings a much wider latitude prevails in the choice of trimming than in the neck opening, and in fact it is only necessary that the edges of the said arm openings be finished in such a manner as to prevent unraveling of the material of the body.

40 I claim:

1. A garment comprising a body portion

having neck and arm openings at the top thereof the lower edges of which openings are in approximate alignment, a trimming immovably fastened to and along the edges of the neck opening and having free portions extending between the front and back of the body to constitute shoulder loops, the edge of said arm openings being finished to prevent raveling and the finishing material terminating in and joining the trimming approximately at right angles thereto, substantially as described.

2. A garment having neck and arm openings at the top thereof the lower edges of which openings are in approximate alignment, a trimming immovably fastened to and along the edges of said neck opening and having portions thereof extending between the front and back of the garment, and constituting shoulder loops, the edges of said arm openings being suitably finished to prevent raveling with the finishing material terminating in the said trimming at the bases of the respective shoulder loops, and a draw string carried by the said trimming.

3. A garment comprising a portion having neck and arm openings at the top thereof the lower edges of which openings are in approximate alignment, a trimming immovably fastened to and along the edges of the neck opening and having free portions extending between the front and back of the body to constitute shoulder loops, a draw string carried by the trimming, and the edges of said arm openings being finished to prevent raveling, the finishing material terminating in and joining the neck trimming approximately at right angles thereto, substantially as described.

WILLIAM S. ELDER.
